J. H. HOLBROOK

LAWN SWEEPER

Filed Dec. 10, 1923

Patented Apr. 13, 1926.

1,580,600

UNITED STATES PATENT OFFICE.

JOHN H. HOLBROOK, OF SULPHUR SPRINGS, TEXAS.

LAWN SWEEPER.

Application filed December 10, 1923. Serial No. 679,560.

To all whom it may concern:

Be it known that I, JOHN H. HOLBROOK, citizen of the United States of America, residing at Sulphur Springs, in the county of Hopkins and State of Texas, have invented certain new and useful Improvements in Lawn Sweepers, of which the following is a specification.

This invention relates to new and useful 10 improvements in lawn sweepers.

The object of the invention is to provide a machine which may be propelled over a grass lawn for the purpose of removing trash therefrom.

15 A particular object of the invention is to provide a machine which will remove leaves, pieces of paper, match stems, bits of metal and all other trash which it may be desired to remove.

20 Another object is to provide a revolving sweeper member having bristles and fingers, whereby both a sweeping and raking action is had and articles too heavy or too smooth to be removed by the flexible bristles, will 25 be carried into the machine by the fingers.

A further object is to provide means for effectively cleaning the sweeping member and removing therefrom adhering articles.

20 A construction designed to carry out the invention will be hereinafter described together with other features of the invention.

The invention will be more readily understood from a reading of the following specification and by reference to the accompanying drawings, in which an example of the 35 invention is shown, and wherein:

Fig. 1 is a side elevation of a machine constructed in accordance with my invention,

40 Fig. 2 is a plan view of the same,

Fig. 3 is a detail of the driving gear,

Fig. 4 is a sectional detail of the bristle cleaner,

45 Fig. 5 is a detail of one of the journals and

Fig. 6 is a detail of the bristle clamp.

In the drawings the numeral 10 designates a collecting trough which is preferably formed of sheet metal upright sides 11. 50 Trunnions 12 are suitably mounted at the front edges of the sides of the trough and engage in ground wheels 13, similar to those used on an ordinary lawn mower. On the inner side of each wheel, an internal gear 14 is concentrically secured. A revolving

55 sweeping member 15 has its shaft 16 suit-

ably journaled in the sides 11 above the trunnions and carries pinions 17 in mesh with the gears, whereby said sweeping member is revolved when the machine is moved 60 forwardly. The yoke of a suitable handle 18 straddles the trough and engages the trunnions 12, outside of the wheels.

The member 15 has a novel construction and comprises a central drum or arbor 19 65 from which a plurality of blades 20 (Fig. 4) radiate. These blades extend longitudinally of the member between the sides 11, of the trough. A flat clamp bar 21 is secured to outer edge of each blade by bolts 70 22. Bristles 23 of fine wire, coarse hair or other suitable material, are held between the blades and the clamp bars. Also rigid fingers 24 of metal or wood or other material are also suitably held by the bar 21 as is 75 shown in Figs. 4 and 6. The rigid fingers or bristles are embedded in the bristles and have their outer ends terminating short of the outer ends of the bristles 23, so as not to interfere with the sweeping operation of 80 the latter.

The rigid fingers are very important because they will engage objects which would not be dislodged by the flexible bristles 23. These fingers are spaced apart in alternate 85 relation to combing fingers 25 carried by a cross-head 27 mounted in the sides 11 of the trough. The fingers 25 are stationary and extend at an angle downwardly toward the sweeping member so that as the latter revolves, the fingers 24 are carried between the fingers 25 and the bristles 23 are carried through flexible bristles 26, also carried by the head. Matter adhering to the member 15 is thus combed off so as to fall into the 90 trough 10 and the sweeper member is kept 95 clean.

A doffer blade 28 is secured to the front edge of the bottom of the trough, rearwardly of the center of the member 15, so that the 100 gathered material may be readily swept into the trough. A sack or other collecting receptacle 29 has a collar 30 fitting around the rear end of the trough. The sack is suitably provided with hooks 31 for engaging eyes 32 105 in the sides 11, whereby the sack is removably attached and may be removed when full.

In using the machine the operator grasps the handle and pushes the machine across 110 the lawn. The wheels 13 impart rotation to the gears 14 which in turn revolve the

pinions 17. The sweeper member 15 is thus revolved in a counter-clockwise direction. The flexible bristles 23 will readily sweep the leaves and lighter objects into the trough, but would slide over newspapers, cards and heavy articles. However these latter will be engaged by the rigid fingers or bristles 24 and carried into the trough.

Various changes in the arrangement and 10 structure of the different elements as well as modifications and alterations, may be made within the scope of the appended 15 claim.

What I claim, is:

15 In a lawn sweeper, a trough, ground

wheels supporting the trough, a revolving sweeper comprising radial transverse blades, bristles secured to outer edges of the blades, rigid fingers also secured to the outer edges of the blades and imbedded therein, said 20 sweeper being mounted so that the bristles and fingers will sweep matter into the trough, and a comb mounted in the trough having bristles and rigid fingers embedded in the bristles, said fingers being spaced so 25 that the fingers of the sweeper will pass therebetween.

In testimony whereof I affix my signature.

JOHN H. HOLBROOK.
